APPARATUS FOR TESTING THE SURFACE HARDNESS OF CONSTRUCTION MATERIALS

Ernst O. Schmidt, Basel, Switzerland, assignor to Arthur R. Anderson, Springdale, Conn.

Application May 29, 1951, Serial No. 228,808

4 Claims. (Cl. 73—79)

1

The invention relates to apparatus for testing the surface hardness of construction materials such as metal, concrete, artificial stone, ceramic products, etc. Apparatus constructed in accordance with the invention comprises a frame adapted to be placed against the surface to be tested, a hammer movable in the frame for impact against such surface, and an indicator associated with the frame to measure the intensity of rebound of the hammer after impact. The hammer is propelled by energy stored therein as by means of a spring or other resilient element arranged between the frame and the hammer.

Experiments have shown that apparatus according to the invention makes possible a rapid and easy testing of surface hardness of construction materials, whether the surfaces be horizontal, vertical, or inclined, whereby the inclination of the test surface requires at most only a correction factor applied to measured rebound intensity for a given inclination.

The hardness of a given material generally bears a relationship to other physical properties of the material, which, within a certain deviation can be determined experimentally. For example, the apparatus has been developed in a form for determining the compression strength of concrete in construction, and has proven itself for this application.

In the drawings which further illustrate the invention in one of its preferred forms:

Fig. 1 is a vertical longitudinal cross-sectional view.

Fig. 2 is a cross-section through A—A of Fig. 1.

A housing 1 of tubular form has at one end a flange 2 with three projections 3 which provide points of support on the surface to be tested. Within housing 1 a test hammer 4 is arranged for movement along the tube axis. It has a square cross-section with corners rounded so that the inside of the tube serves as a guide. A longitudinal slot 5 running the length of the lower side of the tube is provided, opposite to which a shorter longitudinal slot 6 is provided. On the outside of tube 1 a longitudinally slideable trigger 7 is provided with an opening 8 through which the operator's finger can be inserted. Trigger 7 is provided at the right-hand end with a throat piece 9 which is attached to trigger 7 through slot 5 from the inside of tube 1, providing a guide for longitudinal motion in slot 5.

At the left-hand end of trigger 7 a catch 11 is provided so that it can engage the shoulder 12 of the hammer 4 when depressed inwardly

2

through slot 5. For this purpose the throat of catch 11 is made somewhat deeper than the wall thickness of tube 1, allowing a slight rotation of trigger 7 as indicated by arrow 13, enabling catch 11 to be disengaged from shoulder 12.

The hammer 4 is hardened steel and is provided with a spherical head 14 at the front end to give a central zone of contact during impact with the test surface. At the rear end of the hammer 4 a cross pin 15 is located so that it travels freely in the two diametrically opposite longitudinal slots 16 in tube 1. On each end of pin 15 grooves 17 are provided to take tension springs 18 which are attached at their other ends to flange 2. Parallel to tube 1 immediately outside longitudinal slot 6 a longitudinal bar 19 is provided with attachment to flange 2 at one end and to cap piece 20 at the other end. On bar 19 a longitudinally movable pointer 21 is provided with a slight friction against free sliding. Pointer 21 can be engaged with a rotatable catch 22 through slot 6. Catch 22 is located in a fork in the end of hammer 4, attached perpendicularly to the axis of tube 1 by pin 23. Catch 22, when viewed in Fig. 1 is rotatable only in a clockwise direction on pin 23.

A scale 24 is located on the outside of tube 1 parallel to slot 6 adjacent to the edge of pointer 21.

To test, for example, the surface of a concrete wall, the apparatus is placed horizontally as seen in Fig. 1 against the selected test location so that it rests on projections 3. The apparatus is held in position by grip 25 with one hand, and with the thumb of the free hand catch 22 is depressed in the direction of arrow 26, rotating on pin 23 to move under pointer 21. Then a finger of the free hand is placed in opening 8 of trigger 7, pressing it against the tube 1 so as to engage catch 11 with shoulder 12 of the hammer 4. Next the trigger 7 is drawn in the direction of arrow 27 to the position 7' indicated by the dot-dash lines on Fig. 1. Hammer 4 is thus moved against tension springs 18. Next trigger 7 is moved in the direction of arrow 13 allowing catch 11 to disengage shoulder 12 of hammer 4, and the energy stored in springs 18 catapults hammer 4 toward the test surface, against which the spherical head 14 of hammer 4 impacts with a definite predetermined energy. The intensity of rebound of hammer 4 is dependent on the hardness of the test surface of the material being tested. Catch 22 at the instant of impact swings outward to the position shown in Fig. 1, and on the return stroke of hammer 4 it engages sliding

pointer 21, moving it along bar 19 to indicate on scale 24 the amount of rebound travel of hammer 4, giving a measure of the hardness of the test surface.

To make further test measurements, pointer 21 is manually moved back each time to the original position so as to be engaged by catch 22 on the rebound of hammer 4.

Although the drawing shows the guide for the longitudinal movement of the hammer to be provided by the tubular housing, other methods of guiding the hammer, such as tracks, could be employed. Moreover, means other than springs 18 could be used for propelling the hammer 4. For example, the force of gravity, through a pendulum-lever arrangement, could furnish a propelling force to the hammer. The hammer could also be arranged as a piston designed to be longitudinally movable in a cylinder closed at one end. By moving the piston against the closed end of the cylinder, a pneumatic pressure could be built up to be used as a propelling force.

Under certain circumstances it is advantageous to employ an insert piece of appropriate material (for example, hardened steel) between the hammer head and the test surface. This insert piece can be fastened to the housing with one side in contact with the test surface, and the other side presented to the impact surface of the hammer. Since several types of inserts may be required to test various materials, the insert piece is preferably removably connected to the housing to facilitate its interchangeability. Moreover, the hammer head can be rigidly, but removably connected to the body of the hammer, allowing a choice of hammer head types to suit variations in conditions or materials under test.

I claim:

1. Apparatus for testing the surface hardness of construction materials comprising a frame, an element mounted on the frame adapted to be placed against a surface to be tested, a hammer movable longitudinally in said frame for creating impact against the surface to be tested, and a propelling resilient element between the frame and hammer to propel the hammer, movement of the hammer longitudinally in a horizontal plane being controlled entirely by said propelling resilient element and an indicator fixed to the frame to measure the intensity of rebound of the hammer after impact.

2. Apparatus according to claim 1 in which

said frame comprises a tubular housing to guide the hammer, said housing having a longitudinal slot, and an operating trigger slidably mounted in said housing and extending through the slot for engagement with the hammer to move it longitudinally against the action of said resilient element, said trigger being movable into a position in which the hammer is disengaged therefrom.

3. Apparatus for testing the surface hardness of construction materials comprising a frame adapted to be placed against a surface to be tested, a hammer movable longitudinally in said frame to impact against the surface to be tested, a resilient element between the frame and hammer to propel the hammer, said frame comprising a tubular housing to guide the hammer, said housing having a longitudinal slot, a longitudinally movable pointer slidably mounted outside of said housing adjacent said slot for movement parallel thereto, a scale on the housing over which the pointer moves, and a catch pivotally mounted on the hammer, said catch arranged to swing into a position in which it extends through said slot for engagement with said pointer to move it on rebound of the hammer.

4. Apparatus for testing the surface hardness of construction materials comprising a frame, an element mounted on the frame adapted to be placed against a surface to be tested, a hammer movable longitudinally in said frame for creating impact against the surface to be tested, and a resilient element between the frame and hammer, said resilient element arranged to propel the hammer and being connected to both the frame and hammer to resist movement of the hammer upon its rebound from the tested surface, and an indicator scale fixed to the frame to show the intensity of rebound as measured by said resilient element.

ERNST O. SCHMIDT.
